Primary Examiner—Cathron C. Brooks*Assistant Examiner*—Austin Murphy(74) *Attorney, Agent, or Firm*—Dinsmore & Shohl LLP(57) **CLAIM**

The ornamental design for a multifunctional clip device, as shown and described.

DESCRIPTION

FIG. 1 is a front elevational view of a multifunctional clip device, embodying my inventive design;

FIG. 2 is a rear elevational view of the multifunctional clip device of FIG. 1;

FIG. 3 is a right elevational view of the multifunctional clip device of FIG. 1;

FIG. 4 is a left elevational view of the multifunctional clip device of FIG. 1;

FIG. 5 is a top plan view of the multifunctional clip device of FIG. 1;

FIG. 6 is a bottom plan view of the multifunctional clip device of FIG. 1; and,

FIG. 7 is a front elevational view of the multifunctional clip device of FIG. 1 further illustrating the latch in an operable position.

The broken lines (and areas defined thereby) shown in the figures are for illustrative purposes only and form no part of the claimed design.
